(57) **CLAIM**

The ornamental design for a breaching tool, as shown and described.

DESCRIPTION

FIG. 1 is an isometric view of a front, top, and left side of an ornamental design for a breaching tool;

FIG. 2 is an isometric view of a rear, top, and left side of the breaching tool of FIG. 1;

FIG. 3 is a left side elevational view of the breaching tool of FIG. 1;

FIG. 4 is a right side elevational view of the breaching tool of FIG. 1;

FIG. 5 is a front elevational view of the breaching tool of FIG. 1;

FIG. 6 is a rear elevational view of the breaching tool of FIG. 1;

FIG. 7 is a top plan view of the breaching tool of FIG. 1; and, FIG. 8 is a bottom plan view of the breaching tool of FIG. 1.

The dash-dash-dash lines depict portions of the breaching tool in which the design is embodied that are not considered part of the claimed design.

1 Claim, 3 Drawing Sheets
